[57] CLAIM

The ornamental design for a handle for a kitchen tool, as shown and described.

DESCRIPTION

FIG. 1 is a front perspective view of a handle for a kitchen tool showing my new design;
 FIG. 2 is a rear elevational view thereof;
 FIG. 3 is a side elevational view thereof;
 FIG. 4 is a top view thereof;
 FIG. 5 is a bottom view thereof;
 FIG. 6 is a cross-section on line 6—6 of FIG. 2; and
 FIG. 7 is a cross-section on line 7—7 of FIG. 2.
 The characteristic feature of the design resides in the configuration of the oblong shaped slot having lengthened bevelled ends thereon.

FIG. 1.

FIG. 2.

FIG. 3.

FIG. 4.

FIG. 5.

FIG. 6.

FIG. 7.
